UNITED STATES PATENT OFFICE.

ELMER S. OLMSTED, OF LOUISVILLE, KENTUCKY, ASSIGNOR TO CHEATHAM ELECTRIC SWITCHING DEVICE COMPANY, OF LOUISVILLE, KENTUCKY, A CORPORATION OF KENTUCKY.

SWITCH-OPERATING MECHANISM.

978,053.

Specification of Letters Patent. Patented Dec. 6, 1910.

Application filed July 1, 1910. Serial No. 569,972.

To all whom it may concern:

Be it known that I, ELMER S. OLMSTED, a citizen of the United States, residing at Louisville, in the county of Jefferson and State of Kentucky, have invented new and useful Improvements in Switch-Operating Mechanism, of which the following is a specification.

My present invention relates to improvements in switch operating mechanism of the type wherein the track switch is thrown automatically and electrically by or under the control of the car as the car approaches the switch, and it has for its object primarily to provide certain improvements in mechanism of this character whereby the switch mechanism is locked so as to prevent a second operation until a car has passed completely over the switch whereupon the switch operating mechanism is automatically unlocked to permit it to be operated by the next car, derailment or other accidents being thereby avoided.

Further objects of the invention are to provide a device for preventing arcing of the trolley circuit between the contacts of the trolley pan during the passage of the trolley wheel, and to provide novel means for protecting and insulating the wires leading to the switch throwing solenoid, a flexible tubular connection being provided in the present instance which will not only prevent the entrance of water or moisture to the solenoid, but also facilitates and maintains such connection.

To these and other ends, the invention consists in certain improvements, and combinations and arrangements of parts, all as will be hereinafter more fully described, the novel features being pointed out particularly in the claims at the end of the specification.

In the accompanying drawing:—Figure 1 is a diagrammatic view of an automatic switch operating mechanism constructed in accordance with the present invention; Fig. 2 represents a transverse section through the trolley pan showing the device for breaking any arc that may form during the passage of the trolley wheel; Figs. 3 and 4 represent in top plan and longitudinal section, respectively, the trolley pan; Fig. 5 is a detail perspective view of the devices for breaking any arc which may form between the parts of the trolley pan during the passage of the

trolley wheel; Fig. 6 is a detail view of the switch for controlling the operation of the solenoid which throws the switch point, illustrating also the co-operative locking device; Fig. 7 shows the parts illustrated in Fig. 6 in side elevation and as viewed from the right, the locking device being omitted; Fig. 8 is a detail perspective view of the solenoid operated contact which establishes a circuit through one or another of the sections of the solenoid which throws the switch point; Fig. 9 is a detail perspective view of the locking device for the movable contact; Fig. 10 represents a transverse section through the switch point operating solenoid and its inclosing box showing the flexible connection for the wires leading to the solenoid; and Fig. 11 represents a transverse section through the flexible connection and illustrating the construction of one of the chocks.

Similar parts are designated by the same reference characters in the several views.

The present invention is an improvement upon the automatic switch throwing mechanism disclosed in Letters Patent, No. 696,313 granted March 25, 1902, and reference may be had to said patent which discloses a generally similar system.

In the present instance, 1 designates the switch point to be operated, it being for example a switch such as used on ordinary street railways, the switch point having a lug 2 attached thereto and this lug is connected by a link 3 to an operating lever 4, one end of this operating lever being fulcrumed on a stationary pivot pin 5 and its opposite end is connected by a link 6 to the core 7 of a solenoid 8, said solenoid having two coils, the coil 9 serving to move the core 7 and thereby throw the switch point into the position shown in Fig. 1, while the coil 10 when energized serves to reverse the position of the core and the switch point. The coil 9 has one terminal grounded while the other terminal is connected to a wire 11. One terminal of the coil 10 is also grounded while its other terminal is connected to the wire 12. The solenoid and the related switch operating mechanism are preferably contained in a closed box 13 which is embedded below the surface of the ground or pavement, and in order to prevent the entrance of water or moisture to the solenoid which would be liable to injure it, the sole

noid coils are inclosed in a water-tight casing 14 which is provided with a nipple 15 through which the wires 11 and 12 extend.

The present invention provides a convenient and efficient connection between the nipple 15 of the solenoid casing and the usual rigid pipe 16 which is buried under ground, this connection consisting of a short length of flexible tubing 17, high grade steam hose being suitable, and one end of this length of tubing is fitted over the end of the pipe 16 which projects a suitable distance into the box 13, while the other end of the flexible tubing is telescoped over the nipple 15 on the solenoid casing. The two ends of the flexible tubing are firmly secured upon the pipe 16 and nipple 15 so as to maintain a fluid-tight connection therewith by a pair of clamps 18, each clamp consisting preferably of a strip of brass or suitable material which surrounds the tubing, and a bolt 19 extends through the opposed out-turned lugs 20 on the ends of the clamp and serves to draw the clamp and the tubing 25 tightly upon the nipple 15 and the pipe 16. A flange 21 preferably extends beyond the lug 20 adjacent to one end of the clamp and fits beneath the opposed end of the clamp so as to maintain an even and continuous 30 pressure upon the tubing, thereby avoiding leakage at that point of the clamp where the bolt is located.

In the present instance the switch throwing solenoid is energized by current taken 35 from the ordinary trolley wire. In the present instance 22 designates the usual trolley wire, and at a suitable distance in advance of the switch is placed a trolley pan which is shown in Figs. 2-4 inclusive. This trolley pan is similar in its general construction 40 to that disclosed in the prior patent aforesaid, the longitudinally extending and oppositely inclined strips 23 and 24 which may be of wood or other suitable insulating material having runway irons 25 and 26 secured to their under sides, the strips 23 and 24 being rigidly secured in fixed relation by transverse blocks 27 and 28, and the trolley wire 22 passes over and spans these transverse blocks. One of the runway irons (the iron 25 in the present instance) is continuous from end to end of the trolley pan. The opposed runway iron 26, however, is divided into a central section 26^a and a pair of end 45 sections 26^b and 26^c, the end sections 26^b and 26^c being insulated from the middle section 26^a and also from the opposed continuous section 25. In the present form of the invention, the middle section 26^a of the trolley pan forms part of the circuit which energizes the solenoid and throws the switch point, while the end section 26^c forms part 50 of a separate locking circuit. Consequently, as the trolley wheel X passes from the middle section 26^a to the end section 26^c, there

is a break in the circuit which will tend to form an arc between the extreme end of the middle section 26^a and the opposed runway iron 25. Such an arc, however, is prevented from forming according to the present invention by a division plate or guard 29 composed of insulating material, this plate or guard being sufficiently narrow to depend through the trolley pan between the adjacent edges of the opposed runway irons 25 and 26, this plate or guard in the present instance being secured to a horizontal plate 30 which is also preferably composed of insulating material and it is secured upon the top of the strips 23 and 24, one end of the plate 29 resting against or adjacent to the cross-piece 28. The division plate or guard 29 will thereby materially increase the air gap between the runway irons 25 and 26 so that the formation of an arc which would interfere with a correct and certain operation of the switch mechanism is prevented.

The operation of the solenoid 8 is controlled by an intermediate solenoid 31 which may be housed in a box or casing 32, and this box or casing may be conveniently supported by a trolley pole or other suitable support. This solenoid 31 is provided with a core 33 and the core carries a moving contact 34 which is capable of operating between a pair of opposed stationary contacts 35 and 36, the contacts 35 and 36 being connected respectively to the wires 11 and 12 leading to the coils or sections 9 and 10 of the solenoid 8. The moving contact 34 is connected by a wire 37 to the middle section 26^a of the runway iron 26, a suitable resistance 38 being interposed in this part of the circuit. The terminals of the solenoid 31 are connected to the trolley wire 22 and the runway iron 25 by the wires 39 and 40 respectively. When the solenoid 31 is energized sufficiently, its core 33 will move upwardly into the solenoid, thereby carrying the contact 34 into engagement with the upper contact 35 and when the solenoid 31 is deenergized, the contact 34 will descend, leaving the upper contact 35 and moving into engagement with the lower contact 36. The solenoid, together with the contacts 35 and 36, is mounted upon an insulating base 41 which may be composed of wood or other suitable insulating material. In order to prevent arcing adjacent to the wooden or insulating base 41 as the movable contact 34 disengages from either of the contacts 35 and 36, I form the moving contact 34 substantially as a wedge, that is to say, it tapers at 42, thereby reducing that portion of the contact 34 adjacent to the base 41 sufficiently to cause only that portion of the contact 34 farthest removed from the insulating base 41 to engage the contacts 35 and 36 and, consequently, when the contact 34 disengages from the contacts 35 and 36, any arc that

may be formed will be a sufficient distance from the base 41 to prevent the arc from burning or charring the base.

According to the present invention, the contact 34 is locked in engagement with either the contact 35 or 36 as the case may be until after the car has completely passed the switch, whereupon such car automatically unlocks the contact 34 so as to permit the switch mechanism to be thrown by the next car. This result is accomplished in the present instance by a double solenoid 43 which may be also contained in the casing 32, it having a pair of coils 44 and 45, one terminal of each of the coils 44 and 45 being grounded at 46 while the remaining terminal of the coil 44 is connected by a wire 47 to the end section 26^a of the trolley pan, a suitable resistance 48 being preferably included in this circuit. The remaining terminal of the coil 45 is connected by a wire 49 to a contact plate 50 of a second trolley pan 51, this second trolley pan being located along the trolley wire at a suitable distance beyond the switch. A suitable resistance 52 may be also included in circuit with the coil 45. The trolley pan 51 may be similar to the one first described, except that it may be shorter, and in addition to the contact plate 50 it has an opposed contact/plate 53, the trolley wheel while passing along the trolley pan 51 riding upon and bridging the plates 50 and 53. The solenoid 43 is provided with a core 54 the end of which carries a locking device 55, this locking device in the present instance embodying a pair of opposed blades 56 which correspond in taper to the beveled or tapered portions 42 of the contact 34. After the contact 34 has been moved into engagement with one or another of the contacts 35 and 36, the locking device 55 may shift into a position in which one of the blades 56 will enter between the tapered portions 42 of the contact, while the other blade 56 will bear upon the exterior of the movable contact, and as the locking device 55 moves in a direction transverse to the line of movement of the contact 34, the device 55 will thereby lock the contact until after the locking device has been retracted by an energizing of the coil 45, the locking device being moved into locked position by energization of the coil 44.

In operation, it will be assumed that the switch point 1 is set for the straight track and that it is desirable to throw the switch point into the position shown in Fig. 1, that is, for a curve or crossover. Under these conditions, the locking device 55 will be in retracted position owing to the passage of the preceding car over the switch. When the trolley wheel X upon the car to throw the switch reaches the trolley pan, the motorman will set the controller on the car to turn the current through the car motors.

The moment the trolley wheel X reaches the middle contact 26^a, a circuit will be completed, starting with the trolley wire 22 and following the wire 39, passing through the solenoid 31 and following the wire 40 to the plate 25. The current necessary to operate the motors of the car will be a relatively heavy one and will include in its circuit the solenoid 31, the current passing through the solenoid 31 from the trolley wire being grounded from the car. The solenoid 31 will be thereby energized with sufficient strength to lift the contact 34 into engagement with the upper contact 35 and as the latter is connected by the wire 11 to the coil 9 of the solenoid 8, the switch point will be thrown for the turn in the track. Immediately after the trolley wheel leaves the section 26^a of the trolley pan it reaches the end section 26^a, the circuit through the solenoid 31 being maintained during the passage of the trolley wheel from the section 26^a to the section 26^a. The current will then proceed from the trolley wire through the wire 39, solenoid 31, wire 40 to the plate or runway iron 25 and from the latter it will bridge by the trolley wheel to the end contact section 26^a. From the latter the current will flow by the wire 47 to the coil 44 of the solenoid 43, this coil being grounded at 46. The current flowing through the coil 44 will operate the core 54 and will thereby carry the locking device 55 into locking engagement with the contact 34 which controls the circuit for the switch throwing solenoid 8. In this way the circuit for the switch throwing solenoid 8 will be locked in closed condition until after the car has completely passed over the switch or, in other words, until after the trolley wheel on the car reaches the second or releasing trolley pan 51. As the trolley wheel leaves the contact section 26^a, the circuit through the solenoid 31 will be broken and the locking device 55 will serve to retain the contact 34 in elevated position. When the trolley wheel reaches the contact plates 50 and 53, it will bridge them, current from the trolley wire then passing from the contact plate 53 through the trolley wheel to the plate 50 and from the latter it will pass by the wire 49 to the coil 45 of the locking solenoid 43, the coil 45 of this solenoid being thereby energized with the result that the locking device 55 will be retracted, leaving the movable controlling contact 34 free for subsequent operation.

If it is desirable to set the switch for the straight track, then the motorman will shut off the current from his car just before the trolley wheel on the car reaches the trolley pan in advance of the switch. After the locking device 55 has been retracted or disengaged from the contact 34, the latter will settle by gravity upon the lower contact 36 which is connected to the wire 12 leading

to the coil 10 of the switch throwing solenoid. When the trolley wheel reaches a point where it will span the runway iron 25 and the opposed section 26^a, a relatively weak current will start from the trolley wire passing by wire 39 through the solenoid 31, thence by wire 40 to contact strip 25 then bridging by the trolley wheel X to the contact section 26^a and after passing through the resistance 38, it will pass by wire 37 to the contact 34. From the latter, the current thus obtained will flow through the lower contact 36 and through the coil 10 of the solenoid, the switch point being thereby shifted in the desired direction. During this operation, the resistance 38 is in series with the solenoid 31 so that the latter while it is included as a part of this circuit will not be energized with sufficient strength to lift the movable contact 34. The locking of the contact 34, however, and also the unlocking thereof is effected as in the first instance.

After a car has thrown the switch in either direction, it will be obvious from the foregoing that the locking device will be operated before the trolley wheel on the car leaves the trolley pan in advance of the switch. The switch cannot be shifted again until after the trolley wheel on the car has passed the switch and has also passed the trolley pan 51 which is beyond the switch, the passage of the trolley wheel under the pan 51 causing an unlocking of the switch throwing mechanism. It is therefore impossible for the switch to be thrown or displaced while the car is passing thereover even should a car following the car upon the switch reach a position where its trolley wheel would coöperate with the trolley pan in advance of the switch, as the car passing the switch will have the control thereof.

I claim as my invention:

1. In switch operating mechanism, the combination of an electrically operative switch throwing device, means for closing a circuit through the switch throwing device to operate the switch, and a locking de-

vice coöperative with the circuit closing means to retain it in predetermined condition during the passage of a car over the switch.

2. In switch operating mechanism, the combination of an electrically operated switch throwing device, circuit closing means for controlling the flow of current through the switch throwing device, an electrically operative locking device arranged to coöperate with the circuit closing means to retain it in predetermined position, and means for automatically releasing the locking device to permit subsequent operation of the switch throwing device.

3. In switch operating mechanism, the combination of an electrically operative switch throwing device, a trolley, circuit closing means operative automatically during the movement of a car for transmitting current from the trolley to the switch throwing device to operate the latter in the proper direction, and a locking device coöperative with the circuit closing means and operative automatically from the trolley to first lock and to subsequently unlock the circuit closing means.

4. In switch operating mechanism, the combination of an electrically operative switch throwing device, a trolley, contact devices thereon controllable by a trolley wheel, a movable contact controllable by said contact devices for transmitting current from the trolley to the switch throwing device, a locking device arranged to engage and disengage said movable contact, and contacts spaced longitudinally of the trolley for operating the locking device to first lock the movable contact to retain the switch in one position and to subsequently unlock the locking device.

In testimony whereof I have hereunto set my hand in presence of two subscribing witnesses.
